(57) **CLAIM**

The ornamental design for a chair cover, as shown and described.

DESCRIPTION

FIG. 1 is a right side elevation view of the chair cover as it overlays a chair, with the left side being a mirror image thereof;

FIG. 2 is a right side view of the chair cover as it overlays a chair;

FIG. 3 is a front elevation view of the chair cover as it overlays a chair;

FIG. 4 is a rear view of the chair cover as it overlays a chair;

FIG. 5 is a top plan view of the chair cover as it overlays a chair; and,

FIG. 6 is a top plan view of the chair cover as it lays flat on a flat surface.

The chair legs, shown in broken lines, are provided for illustrative purposes only and form no part of the claimed design.
